[57] **CLAIM**

The ornamental design for a toy water canal section, as
shown and described.

DESCRIPTION

FIG. 1 is a perspective view of a toy water canal section
of the present invention;

FIG. 2 is a perspective view of a modified form thereof;
FIG. 3 is a side elevational view of the design of FIG.

1;

FIG. 4 is a top plan view thereof;

FIG. 5 is an end elevational view thereof;

FIG. 6 is a bottom plan view thereof;

FIG. 7 is an end elevational view of the design shown in
FIG. 2;

FIG. 8 is a bottom plan view thereof;

FIG. 9 is a top plan view thereof.
